his attorney.

UNITED STATES PATENT OFFICE.

JOHN HERBERT KING, OF CINCINNATI, OHIO.

TRAIN-STOPPING APPARATUS.

No. 823,281.

Specification of Letters Patent.

Patented June 12, 1906.

Application filed April 8, 1905. Serial No. 204,473.

To all whom it may concern:

Be it known that I, JOHN HERBERT KING, a citizen of the United States of America, and a resident of Cincinnati, in the county of Hamilton and State of Ohio, have invented certain new and useful Improvements in Train-Stopping Apparatus, of which the following is a specification.

This invention relates to certain improvements in that class of devices which are especially designed for use for stopping railway-trains and by the use of which such trains may be automatically stopped by authorized persons along the line of railway when approaching points of danger—such as broken tracks, bridges, &c., and stalled or wrecked trains; and the object of the invention is to provide a device of this general character of a simple and inexpensive nature and of a convenient and compact structure by the use of which persons along the line of railway may quickly and certainly stop approaching trains, whereby accidents and collisions are effectually prevented and the uncertainty of operation and comprehension of warnings and signals which is liable to occur during fogs, storms, and from inattention of engineers is wholly avoided.

The invention consists in certain novel features of the construction, combination, and arrangement of the several parts of the improved train-stopping device whereby certain important advantages are attained and the device is rendered simpler, cheaper, and otherwise better adapted and more convenient for use, all as will be hereinafter fully set forth.

The novel features of the invention will be carefully defined in the claim.

In the accompanying drawings, which serve to illustrate my invention, Figure 1 is a side elevation showing the forward truck, pilot, and parts of the frame of a locomotive-engine, together with a portion of the railway-track and equipped with a stopping device embodying my improvements; and Fig. 2 is a front elevation of the parts seen in Fig. 1, but on a larger scale, the truck and the pilot being omitted. Fig. 3 is an enlarged partial plan view of the parts seen in Fig. 2. Fig. 4 is a view somewhat similar to Fig. 2, but drawn to a smaller scale and showing a modified arrangement of the improved train-stopping mechanism.

Referring first to Figs. 1 to 3, 1 indicates a portion of the frame of an ordinary locomo-

tive-engine, to which the pilot is attached in the ordinary way, and 2 indicates the forward truck or wheel, while 3 indicates the railway-rail rested upon the ties 4. Upon the frame 1 of the forward part of the engine is secured a bracket 5, having an arm 6 horizontally extended toward and beyond one side of the engine-frame, so as to overlie the ends of the ties 4 where the same project outside the track-rails 3. The extremity 7 of the projecting arm 6 of bracket 5 is bent downwardly toward the ties 4, but has its lower edge sufficiently elevated to permit it to clear the rails, as is requisite in order that the engine may pass switches, sidings, and the like without breakage of the parts. 8 indicates a pipe carried upon the engine-frame and designed to contain air under pressure, said pipe being connected with and forming part of the train-pipe of the air-brake apparatus upon the engine, and in said pipe 8 is arranged an exhaust-valve 9 of any desired construction, the plug or stem of which is provided with an arm 10, having connection with a spring 11, the opposite end of which is secured upon the engine-frame 1 in such a way as to cause the tension thereof to be exerted to move the arm 10, and through it to turn the valve-plug into opened position in order to thereby exhaust the air from pipe 8 and lower the pressure of the air in the train-pipe and brake-cylinders, so that the air-brakes will be automatically set in the ordinary way. At 13 is a ring or eye carried on the engine-frame 1, and 12 represents a cord or similar easily-broken connection, one end portion whereof is passed through the ring or eye 13 and is attached to the arm 10 of the valve-stem, while the opposite end of said cord or fragile connection 12 is extended horizontally beneath the arm 6 of bracket 5 in a plane above the level of the rails 3 and is connected in any preferred way, as seen at 14, with the downwardly-extended extremity 7 of said bracket-arm. 15 represents an actuating device herein shown as formed of a metal frame having at its upper part an inclined sharpened or knife edge 16 and provided with prongs or points 17 and 19, adapted to be engaged in the upper part of one of the ties 4 in such a way as to cause said frame to be supported upon the tie with its inclined knife-edge 16 in position to engage and cut or sever the cord or fragile connection 12 when the engine carrying the same shall have reached a position opposite the tie whereon

frame 15 is secured. As herein shown, the frame 15 has opposite lateral wings or arms 18 18, designed to rest upon the top surface of the tie 4 to steady the frame and prevent the 5 same from being tipped or toppled over when the cord or connection 12 strikes upon the knife-edge 16.

As herein shown, the rearmost prong or point 17 is set at a forward and downward inclination from the under surface of the frame 15, so that said prong or point is adapted to be driven into the rear surface of the tie 4, as seen in Fig. 1, and the prongs or points 19 are formed in line with the lateral arms or projections 18 18, two of said last-named prongs or points being near the extremities of the arms themselves; but it will be evident that this arrangement is immaterial to my invention, and, if desired, the prongs or points may 20 be omitted and apertures may be produced in desired positions in the frame to receive spikes or nails driven into the tie 4.

The frame or actuating device is of a light, strong, and compact nature and may be in 25 charge of the train-crew or may be in the care of stationmen, track-walkers, and other attendants, so that in case of necessity such employees as may be present at a point of danger upon the line may quickly and conveniently set said frame or device 15 in position upon the tie to cut or sever the cord or 30 fragile connection 12 at the pilot of an approaching engine, and thereby to automatically set the air-brakes to stop the train before accident is possible, and in this way it will be seen that the apparatus is capable of 35 operation in a substantially automatic and certain manner and does not depend for efficiency upon the care, attention, or judgment of the enginemen in charge of the approaching train. It will also be apparent that the improved apparatus avoids all liability of accidents arising from inability or 40 failure of the engineman to understand or comprehend warnings and signals, as frequently occurs in the use of other devices and particularly during fogs and storms. It will also be apparent from the above description that the improved train-stopping apparatus 45 constructed according to my invention is of an extremely simple and inexpensive nature and requires but little change in the brake

apparatus commonly in use, being for that reason especially well adapted for employment in railway service, and it will also be obvious that the device is capable of some modifications without material departure from the principles and spirit of the invention, and for this reason I do not desire to be understood as limiting myself to the precise form 60 and arrangement of the several parts of the device herein set forth in carrying out my invention in practice. For example, in Fig. 4 I have shown a modified arrangement of the improved apparatus wherein the exhaust-valve 9 has a laterally-directed arm 20, the free end of which is adapted for engagement with a cam projection 15^a, similar to the frame or actuating device 15 above referred to and secured upon the tie 4. The opposite end of arm 20 has a V edge 21, adapted for engagement with the bent end of a spring 22 on the engine-frame, which normally holds the valve in closed position except when the arm 20 on contact with the inclined cam-surface of the frame 15^a is elevated in such a way as to force the V edge of the arm out of engagement with said spring 22, and thereby open the exhaust-valve 9 of the train-pipe on the locomotive. 75

Having thus described my invention, what I claim, and desire to secure by Letters Patent, is—

A train-stopping apparatus comprising a train-pipe connected with the brake mechanism and having an exhaust-valve, a projecting arm for said valve, a bracket secured to the engine and having a horizontal arm extended outwardly, the outer end of said horizontal arm being bent downwardly to aline 85 with said valve-arm, a fragile connection having one end secured to said valve-arm and the opposite end secured to said downwardly-bent end of the horizontal arm, a spring connected to the opposite end of said valve-arm 90 and secured to the engine, and an actuating device having an inclined knife-edge to engage said fragile connection. 95

Signed at Cincinnati, Ohio, this 27th day of March, 1905.

JOHN HERBERT KING.
